INSERTABLE ELASTIC STRIP

Mayne M. Madson, Hinsdale, Ill., assignor, by mesne assignments, to Maco Industries Inc., a corporation of Illinois

Filed Oct. 28, 1963, Ser. No. 319,359
4 Claims. (Cl. 29—129.5)

This invention relates to elastic material which is adapted to be inserted into and retained by a machine operating member and it particularly relates to an insertable elastic strip adapted to be used with various operating elements, such as feed rolls or pull rolls for various materials, such as paper or corrugated cardboard, and also in scoring operations on corrugated cardboard.

In industry, there are many applications wherein elastomeric materials are bonded or connected in some manner to operating members, such as metallic sleeves or rollers. Common use of such devices is found in the paper and cardboard box industries wherein rubber or plastic materials are molded directly on or cemented to metallic rolls used for feeding or pulling cardboard or paper during various stages of their processing.

However, it is common, particularly in the case of rubber, to have the elastic material deteriorate or become damaged, whereby a portion of or all of the elastic material must be replaced. Often, this means several hours of down time for a particular machine or even for an entire production line. This results from the fact that the entire feed roll or pull roll must be disassembled from the machine and another feed or pull roll must be placed on the machine. The removed roll or operating member must then be sent back to the manufacturer and the damaged or deteriorated elastic material must be replaced. Sometimes, if a spare roller is not available, several days of down time may result before the repaired roller is returned. Thus, it would clearly be highly advantageous if elastic material on a machine operating element could be replaced either partially or entirely, without dismantling the entire machine and replacing the operating element.

Furthermore, not only is it important that the elastic material be readily replaceable, but it is also of great importance that the elastic material be adaptable to be firmly and securely maintained in place on the operating member. Thus, even if the elastic material is replaceable on the operating member without dismantling the entire machine, there is the added problem of attaining an appropriate bond. Although the material could conceivably be cemented to the machine, it is often quite difficult to obtain a firm and lasting bond between the elastic material and a metallic surface, particularly with unskilled personnel; also, cements and adhesives are often difficult to handle and apply. Therefore, it would clearly be highly desirable if the elastic material could be bonded or connected to an operating element of the machine without the necessity of using glue or cement.

It is therefore an important object of this invention to provide elastic or elastomeric material adaptable to be inserted and firmly maintained in place on an operating element.

It is a further important object of this invention to provide an insertable elastic strip of material which may be retained in place on a machine operating element without the use of cement or glues.

It is also an object of this invention to provide a strip of elastomeric material which may be easily and readily inserted in or removed from a groove provided in a cooperating operating element, while at the same time avoiding the necessity of using adhesive means for firmly retaining the strip in place on the operating element.

2

It is an additional object of this invention to provide an elongated strip of elastic material adaptable to be connected to an associated operating member, wherein the strip is provided with a retaining portion which is insertable into place on a groove provided in the operating member.

It is still another object of this invention to provide a strip of elastic material adaptable to be retained in a groove provided in an associated machine operating member, wherein the retaining portion is of less cross-sectional area than the cross-sectional area of the groove so as to provide for easy insertion of the retaining portion in the groove and also so as to provide for frictional retention of the strip within the groove upon application of pressure to the strip.

Further purposes and objects of this invention will appear as the specification proceeds.

A particular embodiment of the present invention is illustrated in the accompanying drawings wherein:

FIGURE 1 is an end elevational view of elastic material in place on a machine roller member;

FIGURE 2 is a sectional view taken along the line 2—2 of FIGURE 1;

FIGURE 3 is a fragmentary sectional view, similar to FIGURE 2, shown during scoring operations on corrugated cardboard; and

FIGURE 4 is a fragmentary, perspective view of the insertable elastic strip.

Referring to the drawings, an operating head or roller 10 of a machine (not shown) is illustrated in association with an elongated elastic strip 12. Although, the operating member 10 is shown as a roller, it is to be understood that the elastic strip may be used in connection with other types of machine members, such as flat members, for example, platens. The cylindrical head 10 shown in the drawings is formed by a pair of semi-circular halves 14 which are securely joined together by means of bolts 16, which pass into the threaded openings 18 in one of the halves 14.

A continuous dovetail groove 22 is provided in the cylindrical surface 20 of the rollers 10 and 17 and passes circumferentially around the head 10. The groove 22 includes a constricted or relatively narrow opening or inlet 24. The opening 24 meets the diverging or downwardly and outwardly inclined walls 26; the walls 26 terminate at the bottom or base 28 of the groove 22, the bottom being substantially parallel to the opening 24. Although the groove would conventionally extend completely around the roller 10, it may pass only partially there-around.

The elastic strip 12 includes an operating or working portion 30 and a retaining portion 32. The operating portion 30 meets the retaining portion 32 along the lower surface 34 of the operating portion 12, the lower surface 34 being in contact with parallel strips of the cylindrical surface 20. Generally, the operating portion 30 is rectangular in cross-section, sides 36 connecting the lower surface 34 to the upper surface 34, which may be contoured to any desired shape. The retaining portion 32 includes a pair of diverging legs 38, formed by a V-shaped groove 40 in the base or bottom 42 of the strip 12. Except in the area of the V-shaped groove 40, the outer surfaces of the retaining portion 32 are adapted to substantially conform to the inner surfaces of the groove 22. Thus, the cross-sectional area of the retaining portion 32, that is, the area bounded by the legs 38, is less than the cross-sectional area of the dovetail groove 22, that is, the area bounded by the walls 26, bottom 28, and opening 24. In this manner, when pressure is applied to the top surface 44 of the operating portion 30, the legs 38 are distorted or forced outwardly and downwardly, thereby moving against the bottom 28 and walls 26 of the groove 22,

whereby frictional engagement between the strip 12 and the groove 22 is provided.

Although the particular construction shown in the drawings is preferred, other forms of the groove 22 and retaining portion 32 may be provided; for example, these co-operating elements may be of other shapes, provided that the inlet 24 be constricted to provide for retention of the strip 12. Also, in order to reduce the cross-sectional area of the retaining portion 32, an opening may pass through the portion 32, rather than providing a V-shaped groove 40 therein.

Since the strip 12 is to be distortable, the strip 12 is constructed of an elastic material, such as rubber or plastic. Also, since the strip is frictionally retained in the groove 22, it is preferred that the material used have a relatively high coefficient of friction. Advantageously, the elastic strip 12 is made of an extrudable or moldable elastomeric material. It is preferred that polyurethane be used since this material is not subject to the same deteriorating effects as rubber. Desirably, the elastic strip 12 has a durometer ranging from about 15 to 98, but preferably, the range is from about 55 to 80.

Referring to FIGURE 3, a scoring element S is shown in operating association with an elastic strip 12 and the operating head 10, a portion of corrugated cardboard C being shown therebetween. As the scoring element S applies pressure to the corrugation C, pressure is transferred to the elastic strip 12 and the legs 38 of the strip 12 are caused to diverge away from each other. Thus, the outer surfaces of the legs 38 are forced into frictional engagement with the walls 26 of the groove 22, and substantially prevent slippage of the strip 12 within the groove 22.

It is thus seen that the above-described invention accomplishes all of the foregoing objects. First, the elastic strip 12 is readily and easily inserted into the groove 22 provided on the machine element or roller 10. Merely by inward compression of the retaining portion 32, insertion of the retaining portion 32 into the groove 22 is possible. Thus, by a simple manual operation, the strip 12 may be connected to the head 10. Using this construction, therefore, an entire strip 12, or portion thereof, may be replaced simply by pulling the retaining portion 32 out of the groove 22, thereby avoiding the necessity of dismantling the entire machine and sending the head back to the manufacturer for repair work. Rather than having several hours or several days of down time for a machine, it is possible to make the necessary repairs in a matter of minutes. Furthermore, when pressure is applied to the strip 12, the unique construction of the strip 12 allows distortion of the legs 38 for frictional gripping of the walls 26 of the groove 22. Thus, it is unnecessary to secure the strip 12 to the operating head 10 by cement or glue.

In summary, applicant's invention provides an easily removable and insertable elastic strip, which is adaptable

to be firmly maintained on an operating element without the use of an adhesive.

While in the foregoing there has been a detailed description of a particular embodiment of the present invention, it is to be understood that all equivalents obvious to those having skill of the art to be included within the scope of the invention, as claimed.

What I claim and desire to secure by Letters Patent is:

1. In combination, a substantially cylindrical operating machine member having a groove circumferentially formed in its outer periphery and with side and bottom surfaces, said groove having a restricted opening, and an integral strip of substantially incompressible elastic material having a working portion and a retaining portion, said retaining portion having leg portions which are received in said groove, said retaining portion having a cross-sectional area slightly less than the cross-sectional area of said groove, the total thickness of the legs taken in a direction parallel to the surface of the machine member and perpendicular to the axis of the groove being substantially the thickness of the restricted opening of the groove, and the side portions of the said retaining portion conforming to the inner surface of both the sides and bottom of said groove whereby upon inward compression of said legs, said retaining portion may be inserted into said groove and after said retaining portion is in said groove, downward pressure against said working portion causes said legs to diverge outwardly against the surface of said sides and bottom of said groove for frictional retention of said strip with said groove.
2. The combination of claim 1 wherein said groove is a dovetail groove, and said integral strip is an elastomeric material having a coefficient of friction sufficient to prevent slipping of said strip within said groove as downward pressure is applied to said strip.
3. The combination of claim 1 wherein said strip is made of polyurethane and said legs are diverging.
4. The combination of claim 1 wherein the durometer of said strip ranges from about 55 to 80.
